UNITED STATES PATENT OFFICE.

WILLIAM J. ELLIOTT, OF PHILADELPHIA, PENNSYLVANIA, ASSIGNOR TO ADOLPH KESSELL, OF PHILADELPHIA, PENNSYLVANIA.

LATCH PROTECTOR OR PRESERVEE.

1,139,262.

Specification of Letters Patent.

Patented May 11, 1915.

Application filed May 20, 1914. Serial No. 839,810.

To all whom it may concern:

Be it known that I, WILLIAM J. ELLIOTT, a citizen of the United States, residing at Philadelphia, in the county of Philadelphia and State of Pennsylvania, have invented a new and useful Latch Protector or Preserver; and I do hereby declare the following to be a full, clear, and exact description of the invention, such as will enable others skilled in the art to which it appertains to make and use the same.

This invention relates to the art of knitting machines, and particularly to the class of dial knitting machines, and one of the objects of the invention is to provide an improved attachment for preserving or protecting the latches of the needle. Heretofore, in such dial knitting machines it is the custom to employ crude devices which continually plow through the needles as the machine is in its course of operation, thereby subjecting the needles to the danger of being broken or otherwise damaged.

Therefore, it is an object of the present invention to protect the needles and the latches thereof and reduce the danger of breakage or damaging to a minimum.

This improved protecting means may be applied to any form or construction of knitting machine, and it is to be understood that the protecting means may be used in coöperation or in conjunction with a machine having a latch opener of the type herein shown and described, which type of opener is similar to that shown and described and claimed in the application filed April 15, 1914, Serial No. 831,978.

In practical fields the minor details of construction may be subjected to various minor alterations, falling within the scope of what is claimed.

The invention comprises further features and combination of parts, as hereinafter set forth, shown in the drawings and claimed.

In the drawings:—Figure 1 is a plan view of a segmental portion of a knitting machine, showing the improved latch protector or preserver as applied, the same being used in conjunction with said latch opener. Fig. 2 is a plan view on an enlarged scale of the latch protector or pre-

server. Fig. 3 is a perspective view of the latch protector looking upwardly thereupon. Fig. 4 is a longitudinal sectional view of Fig. 2.

As before stated, any form or construction of knitting machine may be employed, therefore 1 designates a stationary or immovable part of the machine. As far as the machine is concerned, it is only necessary to illustrate a sufficient number of parts to carry out the operation of the invention. Carried by the stationary part of the machine is a plunger 2, in the form of a roller. In practice, however, a number of these plungers is to be employed for actuating the dogs 3, only one being illustrated. The plunger 2 at certain periods is designed to be cammed upwardly through the stationary part or bed plate 1 by any suitable means (not shown). Engageable with and movable in an annular recess of the bed plate or stationary part is the usual movable arched ring 4, which carries the dog 3. Said annular recess is designated by the numeral 5. Also movable with the arched ring are the upper and lower dial plates 6 and 7, being secured together in the usual manner by the screws 8. The dial plate 7 is provided with the usual circular or annular slot 9 having the camming portions or surfaces or edges 10, in which slot the lugs 11 of the needles engage, so that when the lower needle actuating dial plate is in the act of rotation, the needles will be actuated in the usual manner by the camming surfaces or portions 10, thereby forcing them radially toward the center of the machine, in order to take and release the thread in the course of knitting. The needle plate 12 is stationary, the same being secured by the screws 13, as shown clearly in Fig. 2, to a stationary dial plate 14, which as shown at 15, is fixed to the bed plate 1.

Pivoted at 17, there only being one shown, is a camming link 18, the free end of which has pivoted to it as at 18^a a link 19, which in turn is pivoted at 20 to the dog 3. A spring 21 connects between the pivot 18 and the arched ring as at 22. When the dog 3 is rocked or moved in the direction of the arrow *a*, the camming link

18 is thrown in the position as shown in Fig. 1, and the dog 3 is held locked in such position by the arm 23 of the pawl 24 engaging the notch 25 of said dog. As shown 5 in Fig. 1 the dog 3 is in the act of being actuated by the plunger or roller 2, the pawl 24 just having been previously tripped by the arm 26 coming in contact with the nose 27 of the plate 28, which is adjustably 10 secured as at 29 to the bed plate or stationary part of the machine. In other words, as the movable dial plate or ring 4 rotates, the arm 26 comes in contact with the nose 27 of the plate 28, thereby causing 15 the arm 23 to disengage from the notch 25 of the dog 3, in which case the spring 21 will throw the dog in the path of the roller 2. As the dial plate or ring 4 further rotates, the dog 3 will cam against the roller 20 2, thereby, through the medium of the link 19, actuates the camming link 18, which in turn will actuate the needles. A spring 30 is provided for holding the pawl in its normal position. As stated, the camming link 25 actuates the needles radially toward the center of the machine, and as they are so moving, the latches 31 of the needles 32 (which are in the radial grooves of the needle plate 12) are opened by the latch 30 opening mechanism 33. These latches are only opened at the time of completing one garment, and starting the knitting of the next garment.

The particular form of latch opening 35 mechanism is shown, described and claimed in the application of William J. Elliott, filed April 15, 1914, Serial #831,978, which mechanism is designed for use in connection with a knitting machine, when 40 the improved latch protector or preserver is employed. However, either one or the other may be used independently.

The latch preserver 64 comprises the bracket plate 65, pivoted at 66, the same 45 being adjustable on said pivot, by means of the set bolt 67, which passes through the segmental slot 68 of said plate. By loosening and tightening the set bolt 67, the plate 65 may be adjusted on its pivot. Adjustably secured in the bore of the plate, that is, of the enlarged end 69 thereof, by 50 means of a set screw 70 is a rod 71, one of its end portions terminating in an enlargement 72, in the aperture 73 of which by 55 means of a set bolt 74 a pin 75 is adjustably secured, the lower end of which terminates in the latch preserver plate 76, which may be disposed at different angles, relative to the travel of the upper and lower dial plates. This latch preserver plate is 60 provided with the usual opening 77, through which the thread is fed, and which thread travels in the cuts or grooves 78, of the under face of said preserver plate, in knitting the

garment. As the upper and lower dial 65 plates are in the act of moving, the latch preserver plate travels over the various needles, as they are projected radially toward the center of the machine in knitting, thereby protecting the latches, as well 70 as the needles. This plate 76 not only protects and preserves the needles, but also acts in preventing the latches from closing. The end 79 of the plate 76 is beveled off or curved off, as shown at 80, so that the plate 75 76 will easily glide over the needles.

The invention having been set forth, what is claimed as new and useful is:—

1. In combination with a knitting machine having a series of latch needles and provided with a revoluble member, a device carried by the revoluble member of the knitting machine for gliding over the latches thereby protecting the same, said device comprising a plate pivoted on said 80 revoluble member and extending radially of the knitting machine, said plate having at one end an elongated slot, means extending through the elongated slot and engaging the revoluble member for holding the 85 plate adjustable on its pivot, the other end of the plate having a socket, a rod mounted in said socket, a set screw for holding the rod adjustable in the socket, one end of the rod having an enlargement, a latch needle 90 protecting plate movable with said revoluble member and in a horizontal plane, said protecting plate having a threading eye and groove at one end, while the other end is rounded off and adapted to glide over 100 the latches of the needle, a pin rising upwardly from the protecting plate, and being mounted adjustable vertically and revolvably in said enlargement, whereby the protecting plate may be adjusted at different 105 angles to the annular movement of the revoluble member.

2. In combination with a knitting machine having a series of latch needles and provided with a revoluble member, a device 110 carried by the revoluble member of the knitting machine for gliding over the latches thereby protecting the same, said device comprising a plate pivoted on said revoluble member and extending radially 115 of the knitting machine, means coöperating with one end of said plate and said member for holding the plate adjustable on its pivot, the other end of the plate having a socket, a rod mounted in said socket, a set screw 120 for holding the rod adjustable in the socket, one end of the rod having an enlargement, a latch needle protecting plate movable with 125 said revoluble member and in a horizontal plane, said protecting plate having a threading eye and groove at one end, while the other end is rounded off and adapted to glide over the latches of the needle, a pin rising

upwardly from the protecting plate, and being mounted adjustable vertically and revolubly in said enlargement, whereby the protecting plate may be adjusted at different angles to the annular movement of the revoluble member.

In testimony whereof I have signed my

name to this specification in the presence of two subscribing witnesses.

WILLIAM J. ELLIOTT.
